ABSTRACT OF THE DISCLOSURE

N,N - dimethyl - N - [CH(CH₃)C₆-C₁₈alkyl] - N - 3-nitro - 4 - methoxybenzyl ammonium chlorides exhibit high germicidal, algicidal and fungicidal activity in hard water.

This invention relates to germicidal, fungicidal and algicidal quaternary ammonium compounds and to methods for their preparation. Quaternary ammonium compounds have enjoyed wide use as antiseptic agents. However, one of the major problems in the quaternary ammonium germicide art has been to find quaternary ammonium compounds which are highly effective, but which are cheap. It is particularly desired to have a cheap quaternary ammonium composition which exhibits high germicidal, algicidal and fungicidal activity in hard water.

It is accordingly a principal object of this invention to provide cheap quaternary ammonium compositions having a high antimicrobial activity and useful as sanitizing agents, algicides, fungicides and deodorants and for other utilities well known in the quaternary art.

It is a further object of this invention to provide compositions that comply with the standards of the United States Public Health Service and of industry in certain sanitation applications such as sanitizing food utensils, disinfecting swimming pools and the like.

A still further object is to provide improved methods for controlling bacteria, fungi and algae in aqueous systems by means of the addition of improved quaternary ammonium compositions.

All of these objects have been attained by the instant invention.

In one of its composition aspects, the present invention is described as residing in the concept of an N,N-di (lower alkyl) - N - [CH(CH₃)R] - N-(R')-ammonium chloride wherein R is alkyl of from 6 to 18 carbon atoms and R' is a member of the group consisting of lower alkyl, lower alkenyl, and benzyl.

As used herein, the term "alkyl" means a monovalent straight- or branched-chain saturated aliphatic hydrocarbon radical. The alkyl radicals envisioned for the purpose of this invention include for example, the branched and unbranched radicals hexyl, heptyl, octyl, nonyl, decyl, undecyl, dodecyl, tridecyl, tetradecyl, pentadecyl, hexadecyl, heptadecyl, octadecyl, and the like.

As used herein, lower alkyl radicals are alkyl radicals as above having from 1 to 6 carbon atoms.

As used herein, the term "lower alkenyl" means straight- or branched-chain aliphatic hydrocarbon radicals having at least one carbon-to-carbon double bond and having from 2 to 6 carbon atoms.

As used herein, the term "benzyl" means the monovalent radical obtained when a hydrogen atom attached to the methyl group of toluene is removed. As will be obvious to one skilled in this art, the substitution of simple moieties on the benzene ring of the benzyl radical, such

2

as lower alkyl, halo (i.e., chloro, bromo, iodo, and fluoro), lower alkoxy, lower alkylmercapto, nitro, and trifluoromethyl, does not adversely affect the germicidal, algicidal, and fungicidal activities of the compositions bearing the benzyl radical on the quaternary nitrogen atom, and such substituted compounds are the full equivalents of the compositions herein claimed.

In another of its composition aspects, the present invention is described as residing in the concept of a composition comprising a mixture of N,N-di(lower alkyl)-N - [- CH(CH₃)R"] - N-(R'')-ammonium chlorides, wherein R" is alkyl of from 6 to 18 carbon atoms having an average of 10.5-11.5 carbon atoms and R'' is a member of the group consisting of lower alkyl, lower alkenyl and benzyl.

An important advantage offered by the compositions of this invention resides in their economy. Not only are the compositions readily prepared from cheap, commercially abundant starting materials, but in addition they are particularly effective as germicides, algicides, and fungicides.

The novel compounds of this invention can be prepared by the following process:

An alpha-olefin is catalytically hydrochlorinated by adding hydrogen chloride to the double bond in the absence of actinic light or peroxides. The resulting 2-chloroalkane is caused to react with a di-(lower alkyl)amine to give 2 - [di - (lower alkyl) - amino]alkane, which, when caused to react with a quaternizing agent, R'Cl (or R''Cl), gives the desired product.

In practice, the hydrochlorination step has been found to proceed readily at reduced temperatures (0-10° C.) in the presence of a Lewis acid. We generally prefer to use stannic chloride, but other Lewis acids, for example, aluminum chloride, ferric chloride, zinc chloride and the like are satisfactory.

The reaction of the 2-chloroalkanes with a di-(lower alkyl)amine is conveniently carried out in aqueous solution, at a pressure of 500-1000 pounds per square inch and a temperature of about 200-250° C. The use of an excess of the amine reduces the formation of unwanted quaternaries at this stage of the process.

Quaternization of the 2 - di - (lower - alkyl)aminoalkane with the quaternizing agent, R'Cl (or R''Cl), is readily accomplished in aqueous solution at about 60-100° C. A slight excess of quaternizing agent is desirable for high yields at this step; the excess is hydrolyzed and removed in the purification of the quaternary.

While the product of this invention can be isolated in the form of a mixture of the pure quaternary salts, we prefer to prepare the compositions in the form of their solutions (aqueous or aqueous-alcoholics) containing approximately 50 percent quaternary. In this form the quaternary mixture is conveniently packaged, shipped and used.

The phenol coefficients of exemplary compositions of this invention are given in Table I, as follows:

TABLE I.—PHENOL COEFFICIENTS OF N,N-DIMETHYL-N-BENZYL-2-ALKYLAMMONIUM CHLORIDES, ALKYL=C₁₁-C₁₈

[Phenol coefficient at 20° C.]

Compound	Staph. aureus	Sal. typhosa
N-benzyl-N,N-dimethyl-2-alkylammonium chloride.	357	286
N-(p-Chlorobenzyl)-N,N-dimethyl-2-alkylammonium chloride.	429	389
N-(Dichlorobenzyl)-N,N-dimethyl-2-alkylammonium chloride.	429	389

3

The anion of the quaternary ammonium salts of this invention is disclosed throughout as chloride, because the chloride salts are the cheapest to product. It will be understood by one skilled in the art that all anions known in the quaternary germicide art are equivalent insofar as their germicidal activity is concerned.

The following examples serve to further illustrate the invention, but the latter is limited thereto:

EXAMPLE 1

(A) 2-chloroalkanes

Three moles of alpha-olefin ($R-CHCH_2$, wherein R is alkyl of from 9 to 13 carbon atoms) having an average molecular weight of approximately 180, and having the following approximate analysis:

Olefin:	Percent
C_{10} -----	1
C_{11} -----	14
C_{12} -----	23
C_{13} -----	23
C_{14} -----	24
C_{15} -----	14
C_{16} -----	1

were caused to react in the absence of a solvent with hydrogen chloride at 1-5° C. in the presence of 5 percent of stannic chloride as a catalyst. The reaction was complete in about eight hours. The catalyst was removed by extraction with dilute hydrochloric acid, water, and dilute sodium bicarbonate solution, and the product was dried over anhydrous magnesium sulfate. The resulting 2-chloroalkanes were obtained in a yield of 97.5 percent as a crude mixture, $n^{25}_D = 1.4438$, which assayed at 100 percent chloroalkane.

(B) 2-dimethylaminoalkane

An autoclave was charged with a mixture containing 1 mole of crude 2-chloroalkane (above), 1 mole of sodium hydroxide as a 50 percent aqueous solution, and 1.5 moles of dimethylamine as a 30 percent aqueous solution. The autoclave temperature was raised to 240° C. over a period of three hours and was maintained at 240° C. ± 2 ° C. for 24 hours. The autoclave pressure was 760 p.s.i. (pounds per square inch). After cooling, the reaction mixture was separated, washed with saturated sodium chloride solution, and dried over anhydrous magnesium sulfate. The 2-dimethylaminoalkane mixture was then distilled. A crude yield of 91.4 percent of theory was obtained.

(C) N,N-dimethyl-N-benzyl-2-alkylammonium chloride

A reaction vessel was charged with 216.0 g. of 2-dimethylaminoalkane (Example 1B) and 47.5 ml. of water, and the mixture was heated to 80° C. During a period of 5.5 hours 105.0 g. of benzyl chloride was added while maintaining a reaction temperature of 80-85° C. Stirring was continued at 80-85° C. for one hour, and the mixture was boiled until the pH was about 7.6. An additional 5.0 g. of benzyl chloride and 25 ml. of water was added in increments with alternate stirring and boiling until the pH of the mixture was 6.8. Ten ml. of 15 percent sodium carbonate solution and heating at 80-85° C. were then required to neutralize the slight excess of benzyl chloride and bring the pH to 8.0. The mixture was then steam distilled for 2.5 hours to remove contaminants. The purified quaternary solution was diluted with 45.0 ml. of distilled water, treated with activated charcoal, and filtered. After washing the filter cake and further dilution of the product with distilled water, there was obtained 522.0 g. of a 53.50 percent solution of N,N-dimethyl-N-benzyl-2-alkylammonium chloride, representing a process yield of 82.7 percent. The phenol coefficients of the product are given in Table I.

4

EXAMPLE 2

N-benzyl-N,N-dimethyl-2-alkylammonium chloride

Following the procedure given in Examples 1A, 1B and 1C, a mixture of N,N-dimethyl-N-benzyl-2-alkylammonium chloride was prepared from alpha-olefins having a chain length of $C_{15}-C_{20}$. The average molecular weight of the product was 414.7 and the solution assayed at 50.21% quaternary.

Biological testing according to standard testing procedures revealed the following phenol coefficients for this product:

Organism:	Phenol coeff. at 20° C.
<i>Staph aureus</i> -----	357
<i>Sal. typhosa</i> -----	388

EXAMPLE 3

N-benzyl-N,N-dimethyl-2-alkylammonium chloride

Following the procedure given in Examples 1A, 1B and 1C, a mixture of N-benzyl-N,N-dimethyl-2-alkylammonium chloride was prepared from a mixture of alpha-olefins having a chain length of $C_{11}-C_{20}$. The average molecular weight of the product was 383.2, and the solution assayed at 49.97 percent quaternary.

Biological testing according to standard testing procedures revealed the following phenol coefficients for this product:

Organism:	Phenol coeff. at 20° C.
<i>Staph aureus</i> -----	428
<i>Sal. typhosa</i> -----	388

EXAMPLE 4

N-allyl-N,N-dimethyl-2-alkylammonium chloride

Following the procedure given in Example 1C, N-allyl-N,N-dimethyl-2-alkylammonium chloride having an alkyl chain length of $C_{11}-C_{15}$ was prepared from allyl chloride and the 2-dimethylaminoalkane described in Example 1B. The average molecular weight of this product was 301.6 and the solution assayed at 50.07 percent quaternary.

Biological testing according to standard testing procedures revealed the following phenol coefficients for this product:

Organism:	Phenol coeff. at 20° C.
<i>Staph aureus</i> -----	440
<i>Sal. typhosa</i> -----	278

EXAMPLE 5

N-(4-chlorobenzy1)-N,N-dimethyl-2-alkylammonium chloride

Following the procedure given in Example 1C, N-(4-chlorobenzyl)-N,N-dimethyl-2-alkylammonium chloride having an alkyl chain length of $C_{11}-C_{15}$ was prepared from p-chlorobenzyl chloride and the 2-dimethylaminoalkane described in Example 1B. The average molecular weight of this product, having the structural formula

was 386.1, and the solution assayed at 53.8 percent quaternary.

The phenol coefficients for this product are given in Table I.

5

EXAMPLE 6

N-dichlorobenzyl-N,N-dimethyl-2-alkylammonium chloride

Following the procedure given in Example 1C, N-dichlorobenzyl - N,N - dimethyl-2-alkylammonium chloride having an alkyl chain length of C₁₁-C₁₅ was prepared from mixed dichlorobenzyl chlorides and the 2-dimethyl aminoalkane described in Example 1B. The product, having the structural formula

had an average molecular weight of 420.6, and the solution assayed at 52.3 percent quaternary.

The phenol coefficients for this product are given in Table I.

EXAMPLE 7

N,N-dimethyl-N-ethylbenzyl-2-alkylammonium chloride

Following the procedure given in Example 1C, N,N-dimethyl - N - ethylbenzyl-2-alkylammonium chloride having an alkyl chain length of C₁₁-C₁₅ was prepared from mixed ethylbenzyl chlorides containing about 70 percent p-ethylbenzyl chloride and about 30 percent o-ethylbenzyl chloride and the 2-dimethylaminoalkane described in Example 1B. The product having the structural formula

had an average molecular weight of 379.8, and the solution assayed at 52.94 percent quaternary.

6

average molecular weight of this product, having the structural formula

was 426.7, and the solution assayed at 50.33 percent quaternary.

10 Biological testing according to standard testing procedures revealed the following phenol coefficients for this product:

Organism: Phenol coefficient at 20° C.
Staph aureus ----- 785
 15 *Sal. typhosa* ----- 722

Moreover, this product was highly effective as a germicidal agent in very hard water, as determined by the Chambers test method.

20

EXAMPLE 9

(A) 2-diethylaminoalkane

Following the procedure given in Example 1B, the 2-chloroalkane mixture prepared as in Example 1A is 25 caused to react with aqueous diethylamine to give a mixture of 2-diethylaminoalkane having an alkyl chain length of C₁₁-C₁₅.

(B) N-benzyl-N,N-diethyl-2-alkylammonium chloride
 30 Following the procedure given in Example 1C, the 2-diethylaminoalkane prepared in Example 9A is quaternized with benzyl chloride to produce N-benzyl-N,N-diethyl-2-alkylammonium chloride having an alkyl chain length of C₁₁-C₁₅.

35 As further illustrations of our invention, the following compositions can also be prepared from 2-dimethylaminoalkane and the indicated quaternizing agent according to the procedure given in Example 1C:

Quaternizing agent	Product
Methyl chloride.....	N,N,N-trimethyl-2-alkylammonium chloride.
Hexyl chloride.....	N,N-dimethyl-N-hexyl-2-alkylammonium chloride.
o-Chlorobenzyl chloride.....	N-(o-chlorobenzyl)-N,N-dimethyl-2-alkylammonium chloride.
p-Bromobenzyl chloride.....	N-(p-bromobenzyl)-N,N-dimethyl-2-alkylammonium chloride.
p-Methylmercaptobenzyl chloride.....	N,N-dimethyl-N-(p-methyl-mercaptobenzyl)-2-alkylammonium chloride.
p-Ethoxybenzyl chloride.....	N,N-dimethyl-N-(p-ethoxybenzyl)-2-alkylammonium chloride.
1-chloro-2-butene.....	N-(2-buteny)-N,N-dimethyl-2-alkylammonium chloride.
3-chloro-4-methylbenzyl chloride.....	N-(3-chloro-4-methylbenzyl)-N,N-dimethyl-2-alkylammonium chloride.
3,4-dimethylbenzyl chloride.....	N-(3,4-dimethyl benzyl)-N,N-dimethyl-2-alkylammonium chloride.
4,5-dichloro-2-methylbenzyl chloride.....	N-(4,5-dichloro-2-methylbenzyl)-N,N-dimethyl-2-alkylammonium chloride.

Biological testing by standard testing procedures revealed the following phenol coefficients for this product:

Organism: Phenol coefficient at 20° C.
Staph aureus ----- 428
Sal. typhosa ----- 333

EXAMPLE 8

N,N-dimethyl-N-(4-methoxy-3-nitrobenzyl)-2-alkylammonium chloride

Following the procedure given in Example 1C, N,N-dimethyl-N-(4-methoxy - 3 - nitrobenzyl)-2-alkylammonium chloride having an alkyl chain length of C₁₁-C₁₅ was prepared from 4-methoxy-3-nitrobenzyl chloride and the 2-dimethylaminoalkane described in Example 1B. The

70 As will be evident to the skilled chemist, the mixtures of alpha-olefins, 2-chloro-alkanes and 2-di(lower alkyl)-aminoalkanes can be separated from one another by physical means, for example, fractional distillation or preferably vapor-phase chromatographic separation, to give the individual alpha-olefins, 2-chloroalkanes, or 2-di(lower alkyl) aminoalkane in essentially pure form. From these intermediates, the individual quaternary ammonium compounds can be prepared in essentially pure form by the methods disclosed herein.

We claim:

1. N,N-dimethyl - N - [—CH(CH₃)R] - N-benzyl-amonium chloride wherein R is alkyl of from 9 to 13 car-

3,532,750

7

bon atoms and benzyl is substituted in the 3-position by nitro and in the 4-position by methoxy.

2. A mixture of

N,N-di-(lower alkyl)-N-[—CH(CH₃)R'']-N-(R''')

ammonium chlorides wherein R'' is alkyl of from 6 to 18 carbon atoms and having an average of 10.5-11.5 carbon atoms, and R''' is benzyl substituted in the 3-position by nitro and in the 4-position by methoxy.

UNITED STATES PATENT OFFICE
CERTIFICATE OF CORRECTION

Patent No. 3,532,750 Dated October 6, 1970

Inventor(s) Crounse, Bonta & Ploss

It is certified that error appears in the above-identified patent
and that said Letters Patent are hereby corrected as shown below:

Column 1, line 60, "pendtadecyl" should read --pentadecyl--.
Column 3, line 13, "(R-CHCH₂," should read --(R-CH=CH₂,--; line
48, "2-dimethylaminalkane" should read --2-dimethylaminoalkane--.
Column 4, line 52, "N-(4-chlorobenxyl--" should read
N-(4-Chlorobenzyl)- --.

Signed and sealed this 15th day of August 1972.
